UNITED STATES PATENT OFFICE

MYRTHA MOFFETT, OF FRESNO, CALIFORNIA

TOOL FOR TYING FENCE WIRES

Application filed June 5, 1931. Serial No. 542,246.

This invention relates to the assembling of parts of line fences of that nature which consist of horizontal wires affixed to fence posts, and vertical wires secured to the horizontal wires at intervals, and which are applied after the horizontal wires have been placed and stretched.

In thus securing the wires together, I make use of wire staples of special form and so that no twisting of the fence wires themselves is necessary; and the object of this invention is to provide an apparatus by means of which such staples may be tightly wound and clamped about the wires in such a manner that the staples are placed under a considerable tension, and the wires are consequently held together and against slipping with considerable pressure.

Fig. 1 is a perspective view of the tool locating and supporting frame of the apparatus, shown as arranged in connection with a fence.

Fig. 2 is a sectional plan of the frame shown in connection with the tool and the fence wires, the tool being initially engaged with the staple prior to the latter being twisted, looking up from below.

Fig. 3 is a similar view showing the staple fully twisted.

Fig. 4 is a sectional elevation of the tool as in place and initially engaged with a staple.

Fig. 5 is a side elevation of the tool detached.

Fig. 6 is a cross section on the line 6-6 of Fig. 4.

Fig. 7 is a cross section on the line 7-7 of Fig. 4.

Fig. 8 is a perspective view of the staple in its initial form.

Referring now more particularly to the characters of reference on the drawings, the fence to be assembled includes horizontal wires 1 and vertical wires 2, the former being secured to the end fence posts before the wires 2 are secured thereto. To initially position the individual wires 2 in place and to also locate and support the tool in its proper position relative to the several wires 1, I provide a frame which consists of a pair

of spaced and connected uprights 3 adapted when in use to be placed behind the wires and to abut against the same, and to be supported by the ground.

Adjacent its lower end the frame is provided with a socketed block 4 to form a temporary support for the lower end of a wire 2 to be secured in place, the socket being disposed centrally between the uprights.

Below the position of the wires 1, blocks 5 are removably mounted in opposed pairs on the forward face of the uprights. Said blocks having upstanding flanges 6 disposed outwardly of the uprights so as to form guide and locating means for the wires 1, as shown in Fig. 1. In this manner the wires 1 engage the upper edges of the blocks at the base of the flanges, and are thus definitely positioned relative to the blocks. Formed with the blocks and projecting part way across the space between the uprights are lateral extensions 7, formed on their back sides with downwardly facing and oppositely aligned saddles 8, which are thus disposed back of the wires 1 and 2, the latter being in front of the wires 1.

The tool to be used with the locating and supporting device comprises spaced bars 9 having a depending bend 10 at their forward ends which are provided adjacent the bottom with outward projecting lugs 11 adapted to seat in the saddles 8. The spacing of the bars is such as to enable them to readily project between the block extensions 7 and the saddles 8 from in front of the same. The front faces of the bends 10 at their adjacent sides or edges are provided with recesses or grooves 12 which are shaped and curved to conform to the bent end portion 13 of the securing staple whose legs 14 then project forwardly in substantially parallel relation to the bars. The spacing of the legs and the bend is such that the staple may be easily engaged with and straddle one of the wires 1 and 2 in the manner plainly shown in Figs. 2 and 4.

Projecting downwardly from bars 9 are blocks 15 which form the support for a cylinder 16 which is turnable and slideable therein. Slidably fitted in the cylinder is a split

spring shank 17 on the forward split end of which are jaws 18, while its rear solid end is threaded for a certain length as at 19. The outer faces of the jaws are tapered at the 5 back and engage the similarly tapered bore of the cylinder, so that upon pulling back on the shank, the jaws will be contracted. The cylinder is disposed so that the space between the jaws when horizontally disposed, 10 is substantially in line with the legs of a staple supported in the bar recesses in the manner previously described.

Turnably mounted on the outer end of the cylinder is a hub 20 having a crank handle 15 arm 21 projecting radially therefrom. The cylinder is provided with ratchet teeth 22 thereabout which are engaged by the dog 23 in the hub, the arrangement being such that the cylinder will rotate with the handle 20 only when the latter is rotated in a clockwise direction. Screwed on to the part 19 back of the hub is a hand nut 24 provided with a radial bar 25 to facilitate its turning. This nut always abuts against the rear end 25 of the cylinder and is partially overlapped and engaged by the hub in a manner to prevent outward movement of the nut relative to the cylinder without interfering with its rotation. The portion of the nut overlapped 30 by the hub is provided with ratchet teeth 26 thereabout, which are cut in the direction opposite to those on the hub. These teeth are engaged by a dog 27 mounted in the hub and arranged to be raised when necessary 35 by a finger pad 28 connected thereto and extending to the exterior of the hub, preferably adjacent the handle arm.

In operation the locating frame is first disposed relative to the fence as shown and 40 described, the wire 2 to be connected is placed in position, and the staple is then engaged with the wires. The tool is then mounted in connection with the frame and so that the bars 9 straddle the wire 2 by engaging the 45 lugs 11 by a downward movement from above the staple with a co-operating pair of saddles. The bars 9 are disposed in front of the portions 10 and above the lugs 11. The tool is then swung down somewhat so that 50 the staple is properly located in the groove 12. With this movement of the tool, a leverage action is imparted to the staple legs, causing the bent end of the staple to snugly engage the wires 1 and 2. With the jaws 55 open and horizontally disposed, the cylinder is advanced so that the staple legs project between the jaws a considerable distance. The jaws are then clamped against the legs by holding the cylinder stationary, releasing the 60 dog 27 from the nut 24, and turning the latter in a clockwise direction to pull the jaw shank in a jaw closing direction. When the jaws are thus tightly engaged with the staple, the cylinder is turned by means of the handle 65 and the staple legs become consequently twist-

ed about each other until they have assumed the position shown in Fig. 3, at which time they are tightly engaged with both wires 1 and 2, and the jaws abut against shoulders 5 formed at the forward end of the grooves. During this operation the flanges 6 prevent the wire 1 from being bent or deflected outwardly by the pulling action of the tool, since the only portion of this wire which is free to thus bend is the very short stretch 75 between the adjacent flanges.

It will be noted that the jaws 18, at the back of their gripping faces, which are relatively shallow, are relieved or cut back as at A so that an opening of considerable size is 80 formed from side to side of the jaws. This feature has been found to be very essential to the proper handling of the staples. The presence of the opening eliminates all chance of the staple legs being gripped at their outer ends, and insures such grip as being had 85 relatively close to the bend of the legs, where a grip is most efficient in the twisting of the staple.

The opening also leaves the ends or points 90 of the staple free to roll or move about as the staple is being twisted, which eliminates all chance of the staple pulling from the jaws with the twisting operation.

The legs of the staple, being of spring steel, 95 then snap off at the jaws, and the cylinder can be retracted. The opening of the jaws, to engage another staple, is done by turning back on the handle arm 21. With this movement the cylinder remains stationary because the dog 23 is then merely backed 100 around the ratchets 22. The dog 27 however being oppositely disposed, is taking hold of the ratchets 26 and will impart a retractive movement to the nut 24. The tool is then removed from the saddles and applied in connection with another wire 1 and saddle unit to again tie the next staple in place. When the wire 2 has been secured at all intersecting points, the frame structure is 105 removed from its position and shifted to where another wire 2 is to be placed. This is easily done by lifting up on the wires 1 sufficiently to clear the flanges 6. The frame structure may then of course be moved along the fence 110 for similar placement wherever desired.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A tool for twisting staples comprising 130

- a turnable member, a support in which said member is turnably mounted, single pair of opposed jaws mounted in said member for common engagement with the ends of the 5 staple-legs, means to clamp the jaws against the legs, and means to then rotate the jaws and member as a unit. 70
2. A structure as in claim 1, with means provided in connection with the support 10 separate from the jaws to initially locate the staple in a definite position relative to the jaws. 75
3. A tool for twisting staples comprising a turnable member, a support in which said member is turnably mounted, jaws mounted in said member for engagement with the ends of the staple-legs, and projecting from one end of the member, a threaded element projecting from the other end of the member and connected to the jaws, means between the jaws and member whereby said jaws will be contracted when the element is moved lengthwise of the member in one direction and vice-versa, a nut engaging the element and abutting against the adjacent end of the member, a handle associated with the member at said end whereby to turn the same. 80
4. A tool for twisting staples comprising a cylindrical member, a support in which said member is turnably mounted, jaws mounted in said member for engagement with the ends of the staple-legs, and projecting from one end of the member, a threaded element projecting from the other end of the member and connected to the jaws, means between the jaws and member whereby said jaws will be contracted when the element is moved lengthwise of the member in one direction and vice-versa, a nut engaging the element 30 and abutting against the adjacent end of the member, a handle associated with the member; means between the handle and member to cause the same to turn together with the 35 rotation of the handle in one direction only, and means between the handle and nut to cause the latter to turn with the handle only when the latter is rotated in the opposite direction. 40
5. A tool for twisting staples comprising a cylindrical member, a support in which said member is turnably mounted, jaws mounted in said member for engagement with the ends of the staple-legs, and projecting from one end of the member, a threaded element projecting from the other end of the member and connected to the jaws, means between the jaws and member whereby said 45 jaws will be contracted when the element is moved lengthwise of the member in one direction and vice-versa, a nut engaging the element and abutting against the adjacent end of the member, a hub about the member and turnably engaging the nut to hold 50 the same against the member, a dog and ratchet mechanism between the member and hub to cause the rotation of the handle in one direction only to turn the member, and an oppositely disposed dog and ratchet mechanism between the hub and nut. 70
6. A structure as in claim 5, in which the dog of the last named mechanism is disengageable at will from its ratchets to enable the nut to be turned in the opposite direction independent of any movement of the handle. 75
7. A tool for tying intersecting fence wires comprising spaced bars adapted at one end to straddle one wire and under and adjacent which bars the other wire passes, means formed with the bars at said end to locate and support a tying staple after the same has been engaged with the crossed wires and a turnable jaw unit provided with the tool 80 for clamping engagement with the ends of the staple and mounted in a definite relationship to the bars. 85
8. An apparatus for tying fence wires together by means of staples at the points of intersection of the horizontal and vertical wires of the fence comprising a frame adapted to be disposed in a vertical position against the horizontal wires of the fence, means on the frame for engagement with said wires 90 to definitely locate them relative to the frame, means on the frame to temporarily support each vertical wire individually in a definite position relative to the horizontal wires and frame, a tool to twist a staple engaged with the crossed wires, and means between the tool and wire locating means to removably locate the tool in a definite position relative to the crossing wires. 95
9. An apparatus for tying fence wires together by means of staples at the points of intersection of the horizontal and vertical wires of the fence comprising a frame adapted to be disposed in a vertical position against the horizontal wires of the fence, said frame consisting of spaced uprights horizontally alined blocks on the uprights projecting outwardly therefrom and on which the horizontal wire rests, flanges projecting upwardly from the blocks outwardly of the plane of the wires to hold one wire in place against the uprights, means on the frame to temporarily support each vertical wire individually in a definite position between the uprights and blocks, a tool including spaced bars to project between the uprights above a horizontal wire and straddle the vertical wire, means between the bars and blocks to removably locate the tool in a definite position relative to the crossed wires and a turnable jaw unit on the tool to be clamped to the ends of a staple engaged with the crossed wires to twist the same. 100
10. A structure as in claim 8, with means provided with the bars to initially locate the 105
- 110
- 115
- 120
- 125
- 130

staple in a definite position relative to the crossed wires and jaw unit.

11. A structure as in claim 8, in which said tool locating means comprises alined saddles fixed with and projecting rearwardly from the box and between the uprights and lugs projecting laterally from the other faces of the bars at their forward end to rest in the saddles.

12. A structure as in claim 8, in which said tool locating means comprises alined downwardly facing saddles fixed with and projecting rearwardly from the blocks and between the uprights; the bars at their forward end being formed with a downward bend, and lugs projecting laterally from the outer faces of said bent portions adjacent the bottom to engage the saddles.

13. A tool for tying a staple about intersecting fence wires comprising spaced bars adapted at one end to straddle one wire and under and adjacent which bars the other wire passes, means to disengageably hold said bars against lateral movement relative to the fence, and a turnable jaw unit mounted in connection with the bars and disposed with its axis in a plane between the bars in facing relation to said one end thereof for clamping engagement with the ends of a staple engaged with the wires at their point of intersection.

14. A structure as in claim 13, in which said bar holding means comprises blocks disposed to the sides of the bars, means to support the blocks from the ground adjacent the fence, and lugs projecting laterally from the bars at said one end, the blocks having saddle-grooves parallel to the lugs in which the latter removably seat.

15. An apparatus for tying horizontal and vertical fence wires together at their points of intersection by means of staples comprising means to temporarily support the horizontal wires, means to support said wire supporting means from the ground and acting therewith to also prevent relative lateral movement of said wires, means arranged in connection with said last named means to temporarily support each vertical wire individually in a definite position relative to the horizontal wires, and a tool to engage and twist a staple engaged with the crossed wires.

16. A structure as in claim 15 in which the tool includes a pair of bars arranged to initially receive the legs of a staple therebetween; there being means between said bars and the wire supporting means to detachably hold said bars against lateral movement relative to the fence.

In testimony whereof I affix my signature.

MYRTHA MOFFETT.
